(57) **CLAIM**

The ornamental design for the interchangeable billiard palm bridge set as shown and described.

DESCRIPTION

FIG. 1 is a top perspective view of an interchangeable billiard palm bridge set, showing the base separately for complete disclosure;

FIG. 2 is a side elevation view of a base without a bridge post thereof;

FIG. 3 is a top plan view of a base without a bridge post thereof;

FIG. 4 is a bottom plan view of a base without a bridge post thereof;

FIG. 5 is a side elevation view of a base with a standard bridge post thereof;

FIG. 6 is a front elevation view of a base with a standard bridge post thereof;

FIG. 7 is a front elevation view of a base with a long jump bridge post thereof;

FIG. 8 is a side elevation view of a base with a long bridge post thereof;

FIG. 9 is a front elevation view of a base with a short jump bridge post thereof;

FIG. 10 is a side elevation view of a base with a short jump bridge post thereof;

FIG. 11 is a front elevation view showing a standard bridge post separately for complete disclosure;

FIG. 12 is a front elevation view showing a long jump bridge post separately for complete disclosure;

FIG. 13 is a front elevation view showing a short jump bridge post separately for complete disclosure;

FIG. 14 is a perspective view showing a standard bridge post separately for complete disclosure;

FIG. 15 is a perspective view showing a long bridge post separately for complete disclosure;

FIG. 16 is a perspective view showing a short jump bridge post separately for complete disclosure;

FIG. 17 is a side elevation view showing a standard bridge post separately for complete disclosure;

FIG. 18 is a front elevation view showing a standard bridge post separately for complete disclosure;

FIG. 19 is a top plan view showing a standard bridge post separately for complete disclosure;

FIG. 20 is a bottom plan view showing a standard bridge post separately for complete disclosure;

FIG. 21 is a side elevation view showing a long jump bridge post separately for complete disclosure;

FIG. 22 is a front elevation view showing a long jump bridge post separately for complete disclosure;

FIG. 23 is a top plan view showing a long jump bridge post separately for complete disclosure;

(Continued)

FIG. 24 is a bottom plan view showing a long jump bridge post separately for complete disclosure;
 FIG. 25 is a front elevation view showing a short jump bridge post separately for complete disclosure;
 FIG. 26 is a side elevation view showing a short jump bridge post separately for complete disclosure;
 FIG. 27 is a top plan view showing a short jump bridge post separately for complete disclosure;
 FIG. 28 is a bottom plan view showing a short jump bridge post separately for complete disclosure; and,
 FIG. 29 is a side elevation view showing a base with a standard bridge post as in FIG. 5 but adjusted to a higher position relative to FIG. 5 for complete disclosure.
